UNITED STATES PATENT OFFICE.

ALBERT FRANKLIN KINGSLEY, OF WASHINGTON, DISTRICT OF COLUMBIA.

LOCOMOTIVE OR OTHER BOILER FURNACE.

SPECIFICATION forming part of Letters Patent No. 748,748, dated January 5, 1904.

Application filed April 26, 1901. Serial No. 57,609. (No model.)

To all whom it may concern:

Be it known that I, ALBERT FRANKLIN KINGSLEY, a citizen of the United States, and a resident of the city of Washington, in the 5 District of Columbia, have invented a certain new and useful Improvement in Locomotive or other Boiler Furnaces, of which the following is a specification.

My invention has reference to that class of 10 locomotive and other boiler furnaces in which for the purpose of promoting combustion and consuming the smoke air is introduced into the fire-box through a deflector or arch of fire-clay or other refractory material 15 which extends from below the flues upward and in inclined position toward the opposite end of the fire-box.

The invention has been designed with more 20 particular reference to the needs of locomotive-engine boiler-furnaces, and it is in that connection that I shall describe it.

I will first describe by reference to the accompanying drawings, forming part of this 25 specification, the manner in which I carry the improvement into effect and will then more particularly point out in the claims those 30 features which I believe to be new and of my own invention.

In the drawings accompanying and forming 35 part of this specification, Figure 1 is a longitudinal vertical section, partly in elevation, of so much of a locomotive as needed to illustrate my invention. Fig. 2 is a plan of the arch. Fig. 3 is a perspective view, and Fig. 4 is a plan, of one of the kinds of slabs used 40 to make the arch—viz., the slabs F. Fig. 5 is a perspective, and Fig. 6 a side elevation, of the slabs G used in the arch. Fig. 7 is a perspective view, and Fig. 8 is a section, of slabs 45 H used in the arch. Fig. 9 represents, in end elevation and in side elevation, one of the spacing or brace blocks I. Fig. 10 is a perspective view of the wedge-shaped bricks J which support the slabs F. Fig. 11 is a front 50 elevation of a locomotive-boiler, partly broken away to show the arrangement of the pipes through which air is supplied to the arch. Fig. 12 is an enlarged section of one of the injectors used. Fig. 13 is a cross-section of 55 a modified form of arch in which water-bars are dispensed with.

In this specification, the word "front" as

applied to the arch or any portion thereof refers to the end nearest the flues or flue-sheet, and the word "rear" refers to the end near 55 est the opposite or door end of the fire-box.

In the drawings, A is the fire-box of a locomotive boiler-furnace. B represents the flues. C is the grate-surface, and D is the door, of any usual and suitable construction. 60

E represents the water-bars, communicating at their ends with the water-legs or water-spaces of the boiler and extending lengthwise of the fire-box from below the flues upward in an inclined direction to a point above 65 the door D. In ordinary locomotives there are usually three of these bars arranged parallel with each other and at equal intervals apart, and they are ordinarily used to support the imperforate or solid fire-clay deflector, which it has been customary to interpose 70 between the grate-surface and the flues. These bars I make use of to support my improved arch or deflector. Said arch is a sectional one, composed of slabs of refractory 75 material, preferably fire-clay. These slabs are of three kinds—those F nearest the flue-sheet, those H at the opposite or rear end of the arch, and those G which intervene between the slabs F H and constitute the body 80 or main portion of the arch. The length of the arch depends upon the length of the furnace or fire-box and can be regulated by varying the number of rows of slabs G which form the main portion of the arch. All of the slabs 85 have approximately the same general dimensions and are, say, about four inches thick, except at the points where the air-conduits are formed in them, at which points they are about six inches thick. The meeting faces 90 or edges of the slabs in adjoining rows are shouldered, so as to form a lap-joint, as indicated at m in Fig. 6, and in each transverse row the interior opposite edges of the two slabs which constitute each row are similarly 95 shouldered to form a lap-joint, as indicated at n, Fig. 5. The two slabs of each transverse row extend practically the width of the fire-box, with their exterior opposite edges meeting the sides of the fire-box. The interior 100 opposite shouldered and overlapping edges of the two slabs which meet over the center water-bar E have their vertical faces separated by a slight interval to permit the lateral

expansion of the slabs which takes place when the latter are exposed to the action of heat without opening or impairing the stability of the lap-joint between them.

5 The slabs G have air-conduits *g*, which are alike in all the slabs. Each slab has two of these conduits, which are imperforate and parallel with one another and extend through the slab in the direction of the length of the 10 arch, and they are so arranged that when the slabs are set in place the conduits *g* in the slabs of one transverse row will register with and form a continuation of the conduits *g* of the corresponding slabs in the next adjoining 15 row. The air-conduits in the slabs H, which constitute the rearmost row, are, however, differently arranged. Each is composed of two converging tubular legs *h h*, which meet in an opening *h'*, that registers with the contiguous mouth of one of the conduits *g* in the next adjoining rows of slabs G, there being one of these V-shaped conduits *h h* and their 20 common opening *h'* for each conduit *g*. These V-shaped conduits stop short of the rear 25 edges of the slabs H and are perforated on top with numerous small holes, as shown, through which the air will be discharged to meet the products of combustion as they pass over the rear end of the deflecting-arch. 30 Similarly the slabs F at the opposite or front end of the arch are also provided with V-shaped conduits. There is, however, but one such conduit in each slab F. The ends of the 35 two legs *ff* of each conduit meet in a common opening *f'* on the edge of the slab F nearest the flues, and they then diverge and open separately through the opposite edge of the slab F in a position to meet and register with the corresponding air-conduits *g g* in the contiguous slabs G.

40 It is desirable in order to prevent cinders from accumulating on the top of the arch and in time filling up against the flue-sheet and also for other purposes to leave an interval—say from six to seven inches in width—45 between the front end of the arch and the flue-sheet. To this end I make use of fire-clay tubular spacing-blocks I, two in number, which are interposed between the flue-sheet and arch, each so placed that the tubular conduit *i*, formed in it, will register at one end with the opening *f'* in one of the slabs F and at the other end with one of the flues K, through which air is supplied to the arch. 50 These spacing-blocks have a joint, in the nature of a lap-joint, with the slabs F; but in order that the angle at which the one stands to the other may be varied to conform to the particular inclination of the water-bars in 55 the furnace to which the arch may be applied I prefer to form this joint as a ball-and-socket joint. To this end in the present instance the ball member of the joint is formed upon the block I, as indicated at *i*, while the socket member of the joint is formed in the slab F, as indicated at *f*². The tubular blocks I keep 60 the arch from slipping down toward the flue-

sheet and act as braces to sustain the weight of the arch as it presses in that direction, and they are therefore made of considerable solidity and strength, as shown. A short section *i*² of iron pipe projects from the tubular conduit *i* of each block I into the boiler-flue, through which air is supplied to said conduit, which pipe serves to support and hold 75 and assure the block in place, as well as to complete the air connection.

70 In ordinary locomotive-furnaces the water-bars F are usually secured at their front ends to the boiler at some distance below the bottom flues. In order, therefore, to make as direct and straight connection as possible between the arch and these bottom flues selected for supplying the air without making the slabs F which form the front row of the arch 85 too bulky and cumbersome, I support these slabs upon wedge-shaped bricks J, interposed between them and the water-bars, which raise said slabs F to such a position that their openings F' will be about on the same level 90 with the air-flues, thus permitting a straight connection between them through the medium of the tubular blocks I, as shown. These bricks are of such dimensions that two of them placed end to end will extend the width 95 of the fire-box, and they have at their meeting edges a lap-joint *o*, similar to the joints *m n*, already referred to. Both of these bricks can be made in one mold and can be interchangeably used. They fit at their tops 100 into a recess on the under side of the slabs F, as shown in Fig. 3. The wall *f*³ of this recess prevents the supporting-brick J from slipping down and holds it in place. The other and thicker wall *f*⁴ of the recess is provided to give more strength to the slab F at 105 the point where the pressure of the portions of the arch above comes upon it.

110 The two boiler-flues through which air is supplied to the arch are shown at K. Air is supplied to these flues through one or more injectors L, arranged to take in air at the front of the engine, the steam-supply for said injectors being controlled by the engineer from the engine-cab in the usual way and 115 through suitable connections. I prefer to use one injector for each flue. The pipe *l* from each injector leads through the smoke-box of the locomotive to its respective flue.

120 The arch thus made, while sectional, is continuous and practically solid upon its under side throughout its width and length. The air-vents or discharge-openings, while concentrated near the rear end of the arch, are located on top of the arch instead of in the 125 side or on the extreme end and in a position where they will not be choked or injuriously affected by the clinker which in process of time unavoidably forms upon the arch. Furthermore, by concentrating these openings 130 in the row of slabs nearest the door of the fire-box and farthest removed from the flue-sheet the full head and volume of air is caused to meet the products of combustion at a point

far enough removed from the flues to permit practically perfect combustion before the gases reach the flues. Then, again, by arranging the air-discharge openings in the manner in which these discharge-openings are, so that they will lie in practically a continuous zigzag line entirely across the fire-box from one side to the other, I obtain a very much more effective and thorough air distribution than otherwise would be practicable and discharge the air in such manner as to insure complete intermixture with the products of combustion. By the combination described the longevity of the arch is materially increased, while the construction itself is so simple that unskilled labor can be used to set up or repair the arch. Only three patterns of tubular slabs are required, or four, including the tubular spacing-bricks, and these can be renewed and replaced expeditiously and cheaply. The injecting apparatus will of course last indefinitely.

On some railroads the water used contains mineral substances, which causes such serious and rapid corrosion that water-bars cannot be used with safety. To provide against any such contingency, I may dispense with water-bars and support the arch, as shown in Fig. 13, from each side of the fire-box on lugs *t*, secured to and projecting from the interior walls of the fire-box. Slots *s* in the exterior opposite ends of the fire-clay slabs engage these lugs, which thus are covered and protected from the flame. By using in the center of this arch a key brick or block *r* of varied thickness the same slabs can be used in fire-boxes of various widths.

Having described my improvements and the best way known to me of carrying the same into effect, what I claim herein as new and 40 of my own invention, and desire to secure by Letters Patent, is as follows:

1. A smoke-consuming device for boiler furnaces comprising a fire-clay arch interposed between the flue-sheet and the grate- 45 surface of the fire-box, said arch being solid and continuous on its under face throughout the width of the fire-box and provided with internal air-conduits which discharge through openings formed in the top face of the arch 50 near the rear end of the latter, and being separated from the flue-sheet by an open space bridged by tubular spacing-blocks which open at one end into the conduits in the fire-clay arch, and at the other end into 55 certain of the flues into and through which air is supplied by injectors, as hereinbefore shown and described.

2. In combination with the fire-box, the flues and the water-bars, the sectional fire- 60 clay arch composed of the slabs *F*, *G*, *H*, constructed, arranged and fitted together and formed with air-conduits and top discharge-openings as described, the supporting-bricks *J* for the slabs *F*, the tubular spacing-blocks 65 *I*, and the described means for supplying air under pressure thereto, as and for the purposes hereinbefore set forth.

In testimony whereof I have hereunto set my hand this 22d day of April, 1901.

ALBERT FRANKLIN KINGSLEY.
